UNITED STATES PATENT OFFICE

2,285,826

MEANS FOR SUPPORTING YARN BODIES

Herbert Naumann, Elizabethton, Tenn., assignor
to North American Rayon Corporation, New
York, N. Y., a corporation of Delaware

Application March 11, 1937, Serial No. 130,319

8 Claims. (Cl. 242—129)

This invention relates to a method of and apparatus for facilitating the winding off of thread or filaments from normally unsupported yarn bodies.

More particularly the present method and apparatus is for use in unwinding yarn bodies not supported on spools, bobbins, or the like to insure that the thread or filaments may be taken off while under a continuous expansive pressure from the beginning to the end of the unwinding operation.

An object of this invention is to provide an apparatus on which the unsupported yarn body is firmly held while the thread or yarn is being taken up by a winding, twisting or other type of thread collecting machine.

A further object of the invention is to construct an apparatus which will insure that the normally unsupported yarn body will unwind freely throughout its entire length and not soften or collapse near its inner portion and therefore be collected under a different tension as was the supported outside portion.

These and other objects of the invention will be apparent from an examination of the specification and drawings.

Referring to the drawings, it will be seen that:

Figure 1 is a top plan view of the apparatus partly in dotted lines.

Figure 2 is a vertical section taken on line 2—2 of Figure 1.

Figure 3 is a vertical section taken on line 3—3 of Figure 2.

Figure 4 is a side elevational view.

Figure 5 is a cross sectional view taken on line 5—5 of Figure 2.

Figure 6 is a top plan view showing the yarn body in expanded position and with the top plate removed.

While this invention is applicable for unwinding any type of thread, filament, yarn or the like, its particular use is in unwinding unsupported yarn bodies such as those used in the artificial silk industry. In rayon plants the regenerated threads or filaments are frequently collected on collapsible spools which are removed from the interior of the body before unwinding and after the yarn has been after-treated and dried or it may be collected by means of a centrifugal spin pot. In either instance, it is necessary to take these unsupported bodies and wind them off on a coning machine or the like. Considerable difficulty has been experienced in the art in accomplishing this operation to insure that the winding or coning is uniform from beginning to end.

By way of illustration of the principles and operation of the invention, the apparatus as shown in the drawings is mounted on the lower step 1 of a conventional coning or winding machine (not shown). A base plate 2 is secured to the lower step 1 by screws 3 and also mounted upon the base plate and secured thereto by the screws 3 is a circular apertured plate 4. A tubular cylindrical member 5 is mounted in the aperture formed in plate 4 and extends upwardly as shown in Figure 2 of the drawings where it is vertically slotted at 90° angles through its periphery for the accommodation of laterally moving wedge members which will be hereinafter described.

Surrounding the cylindrical member 5 is a second tubular member 7 formed of four separate quadrants or sectors each of which has affixed to its inner face upper and lower wedge members 8 and 9. The quadrants 7 rest on bottom plate 4 and are yieldably held in position around cylinder 5 through the medium of flat springs or elastic bands 10 set in grooves provided in the outer surface of the quadrants.

Vertically movable within the inner cylinder 5 is a plunger or follower 11 formed with upper and lower angled or oblique shoulders 12 which, as shown, rest against and are of a complementary angle to the oblique faces of upper and lower wedges 8 and 9.

Centrally secured to the middle portion of the plunger or follower 11 is a depending rod 13 having a coiled spring 14 concentrically arranged and tensioned around the upper portion thereof between the bottom of the middle section of the follower 11 and the base plate 2. The depending rod 13 projects downwardly through openings formed in the base plate 2 and lower step 1 where its lower end terminates in a bifurcated pivot 15 and supports therein a pivot pin 16 on which is mounted a lever 17. The upper end of the lever 17 is pivotally secured to a fitting 18 supported from the lower step while the opposite end of the lever 17 carries a treadle operating plate 19.

A latching device 20, comprising a depending box-like bracket having a notch 21 formed therein, encompasses the pivoted lever 17 near its lower end, and it will be obvious that the lever may be latched under the notch 21 to hold the follower or plunger 11 in downward position against the tension of the spring 14. It will also be appreciated that when the lever 17 is disengaged from the notch 21 it will be carried upwardly as indicated in dotted lines in Figure 3 and follow

the upward movement of the plunger or follower 11.

When the lever 17 is unlatched from the notch 21 the spring tension of coil spring 14 forces the follower 11 upwardly to simultaneously contact the oblique portions 12 bearing against the wedges 8 and 9 so as to press the quadrants or sectors 7 outwardly against the tension of the resilient members 10.

In operation the foot treadle 19 is depressed by the operator and lever 17 latched beneath the notch 21 to reduce the diameter of the quadrants whereupon an unsupported yarn body, shown in dotted lines in Figure 2, is placed over the cylinder formed by the quadrants. A circular top 22 carrying a depending centering pin 23 is placed in the tubular extension 24 provided in the upper section of follower 11 and the thread or filaments on the yarn body carried upwardly to the winding or coning machines. The operator then moves the lever 17 out of engagement with the notch 21 to permit the spring 14 to commence forcing the wedges 8 and 9 outwardly to create a uniform outward thrust or expansion on the inside of the yarn body. As the unwinding continues the outer layers of the yarn body are removed and consequently the thickness and strength of the body decreases and under this weakening of the body the quadrants 7 are projected or expanded further and further outwardly to compensate therefor. Consequently, the unwinding progressively proceeds under precisely the same conditions from beginning to end and therefore the cone or spool being wound receives its layers of yarn under the same winding factors throughout and the yarn body is unwound to the last inside layer.

It is obvious that many variations may be made in utilizing the above invention and it is not intended to limit it to the particular embodiment shown and described as illustrative of a single application of it. The terms used in describing the invention have been used in their descriptive sense and not as terms of limitation and it is intended that all equivalents thereof be included within the scope of the appended claims.

What I claim is:

1. An apparatus for insuring the uniform unwinding of a normally unsupported hollow yarn body which includes a cylindrical support for said hollow body, expandable members radiating from said cylindrical support, and resilient means for exerting a continuously expanding pressure on said expandable members.

2. An apparatus for supporting a hollow unsupported yarn body during the unwinding of said body which includes, a split cylinder over which said hollow yarn body is adapted to be positioned, inwardly projecting wedge members carried by the segments of said split cylinder, a spring projected follower positioned interiorly of said cylinder, cam surfaces on said follower normally urging said wedge members outwardly, and latch means for restraining said follower.

3. In an apparatus of the character described which includes a base supported cylinder, equi-spaced vertical slots formed in the periphery of said cylinder, a plurality of exterior arcuate quadrants having right angled oblique faced lugs formed on their inner faces adapted to ride in said slots, a resilient element urging said quadrants into contact with the periphery of said cylinder, a vertically movable plunger in said cylinder, a tapered flange on said plunger adapted to contact with and force outwardly the oblique faced lugs on said quadrants, a rod affixed to and depending from said plunger, a coil spring arranged on said rod between the plunger and cylinder base, a pivoted lever secured to the lower end of said rod and a latch engaging said lever when the same is depressed to place said spring under compression.

4. An apparatus for use in the unwinding of unsupported hollow yarn bodies which includes expandable members adapted to receive said yarn body, means to support said members, and spring-actuated means within said expandable members adapted to continuously increase the expansion of said members as the unwinding of the yarn body progresses.

5. Apparatus for insuring the uniform unwinding of a normally unsupported hollow yarn body comprising, relatively movable members together defining a generally cylindrical body adapted to receive thereover a yarn body, and resilient means continuously exerting a pressure against at least one of said members to move the same outwardly in a radial path.

6. Apparatus for insuring the uniform unwinding of a normally unsupported hollow yarn body comprising, relatively movable members together defining a generally cylindrical body adapted to receive thereover a yarn body, and means including a coil spring continuously exerting a pressure against at least one of said members to move the same outwardly in a radial path.

7. Apparatus for insuring the uniform unwinding of a normally unsupported hollow yarn body comprising, relatively movable members together defining a generally cylindrical body adapted to receive thereover a yarn body, and resilient means continuously exerting a pressure against at least one of said members to increase the cross-sectional area of said generally cylindrical body.

8. Apparatus for insuring the uniform unwinding of a normally unsupported hollow yarn body comprising, members each presenting a surface conforming generally to a portion of the surface of the cylinder and together defining a generally cylindrical surface adapted to receive thereover a yarn body, said members being relatively movable in a path on a radius of the defined cylindrical surface, and resilient means for continuously urging at least one of said members radially outwardly to increase the cross-sectional area defined between the members.

HERBERT NAUMANN.
